(57) **CLAIM**

I claim the ornamental design for a shelf divider with separator, as shown (as described).

DESCRIPTION

FIG. 1 is a perspective view of a first embodiment of the shelf divider with separator;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is a second embodiment of the shelf divider with separator of FIG. 1.

The broken lines are for the purpose of illustrating the environment of the design only and form no part of the claimed design.
